UNITED STATES PATENT OFFICE.

ARTURO G. FAUZON, OF CLEVELAND, OHIO, ASSIGNOR TO THE OAK RUBBER COMPANY, A CORPORATION OF OHIO.

HYDROGEN-GAS GENERATOR.

Application filed January 11, 1923. Serial No. 612,096.

To all whom it may concern:

Be it known that I, ARTURO G. FAUZON, a citizen of Argentina, residing at Cleveland, in the county of Cuyahoga and State of 5 Ohio, have invented certain new and useful Improvements in Hydrogen-Gas Generators, of which the following is a specification.

This invention relates to hydrogen gas generators, and more particularly to a portable device for generating gas for inflating 10 toy balloons and similar purposes.

The main object of the invention is to provide a hydrogen gas generator which will produce gas chemically by the action of 15 a solution of water and oil of vitriol upon spelter or zinc without danger of explosion.

Another object of the invention is to provide a gas generator of said character, which is of simple and inexpensive construction, 20 and economical in use.

With the above and other objects in view the invention will be hereinafter fully described as illustrated in the accompanying drawings, and the novel features thereof will 25 be distinctly pointed out in the appended claims.

In the drawings similar characters of reference are used to designate corresponding parts.

30 Figure 1 is a front view of a gas generator constructed in accordance with my invention.

Fig. 2 is a sectional elevation taken on line 2—2 of Figure 1,

35 Fig. 3 is a longitudinal sectional view of the condenser tank,

Fig. 4 is a cross-sectional view taken on line 4—4 of Fig. 3,

Fig. 5 is a similar view taken on line 5—5 40 of Fig. 3, and

Fig. 6 is a plan view illustrating the incline for draining the bottom of the condenser tank into the conduit.

Referring to the drawings, 1 represents a 45 lower compartment, the rear side 2 of which extends above its top 3 and supports a reservoir 4 for holding a solution of water and oil of vitriol. A suitable opening 5 is provided in the top of the feed reservoir 4 for filling the same. Upon the bottom of the 50 lower compartment 1 is arranged a box constructed of a bottom plate 6, sides indicated by 7, and a top plate 8 provided with perforations 9. Suitable blocks 10 are arranged 55 between the plates 6 and 8 for supporting

the latter, which is adapted to carry spelter or pieces of zinc indicated by 11. A pipe 12 is adapted to conduct the solution of water and oil of vitriol from the reservoir 4 to the space 13 between said plates for coming in contact with the spelter or pieces of zinc 11 to produce hydrogen gas. Spelter or zinc is supplied to the lower compartment 1 through an opening 14 provided in its top 3, and this opening is closed by means of a 60 flanged collar 15, to which is fixed a removable cover 16 by means of an ordinary clamp and screw indicated by 17, or in any other suitable manner. A gasket 18 is arranged between the flanged collar 15 and a cover 16 65 for preventing leakage at this joint.

In order to prevent explosion of the gas generated in the lower compartment 1, said gas passes upwardly through a conduit 19 into one end of the condenser tank 20 and 70 out from the other end thereof through a tube 21. Said condenser tank is preferably cylindrical in cross section and is supported as at 22 to the rear side 2. A plurality of 75 partitions 23 and 24 are arranged crosswise 80 and alternately in the condenser tank 20, and the former are perforated at their upper portions as indicated at 25 and the latter at their lower portions as at 26. Said partitions direct the gas through the condenser tank from the conduit 19 to the tube 21 in an up and down direction, as indicated by 85 the arrows, for increasing the cooling efficiency of the tank. The lower edge of each of said partitions is provided with an 90 opening as at 27 for permitting the moisture from the cooling gas to drain into the conduit 19 and back to the lower compartment 1. An incline or notch is provided at 28 95 for facilitating the drainage from the bottom of the condenser tank into the conduit 19 and for directing the same to the side of said conduit. A shut-off valve 29 is arranged in the tube 21, and extending therefrom is a nozzle member 30 for the attachment of a toy balloon, indicated by 31, to be inflated. Said nozzle member is provided with a quick acting shut-off valve 32. It will be understood that all parts of the 100 generator are constructed of corrosive resisting materials.

In practice, spelter or pieces of zinc are introduced through the opening 14 into the lower compartment 1 and is supported by the perforated top plate 8 of the box at the 105

bottom of said compartment, and the cover 16 is clamped in position to seal said opening. The reservoir 4 is supplied with a solution of water and oil of vitriol through 5 the opening 5, which opening is not closed. As the solution rises through the perforations of the top plate 8 of the box in the lower compartment 1 it comes in contact with the spelter or pieces of zinc, and this 10 action generates hydrogen gas. The gas rises and passes through the conduit 19 into the condenser tank 20 and therethrough as directed by the partitions 23 and 24, as shown by the arrows, and into the tube 21. If it 15 is desired to utilize the gas for inflating a toy balloon, or other purposes, a balloon 31 is attached to the nozzle member 30 and the shut-off valve 29 opened and the other shut-off valve 32 manipulated to admit to and 20 shut off from the balloon the gas as will be understood. In case the gas generated in the lower compartment 1 is not used, it will rise and pass into the condenser tank 20, cool and the moisture therefrom drained 25 back into said lower compartment. Should the pressure of the gas in the lower compartment become sufficient, it will force the solution in said lower compartment back through the perforations 9 of the top plate 8 and up through the pipe 12 into the reservoir 4, and the gas will escape through 30 the opening 5, and thus eliminate danger from explosion.

From the drawings and description, it 35 will readily be seen that this generator is capable of producing hydrogen gas at small expense, and that there is no danger from explosion when the gas is generated faster than it is being used or even if not used. 40 It will be understood that slight changes in the details of construction may be made within the scope of the claims.

Having fully described my invention, what I claim is:

45 1. In a hydrogen gas generator, the combination of a compartment, a box in the compartment, the box having a top adapted to support spelter or pieces of zinc, the top being perforated, a feed reservoir above the 50 compartment, a pipe establishing communication from said reservoir with said box below its perforated top, a condenser tank above said compartment, a conduit extending from said compartment to the condenser tank, and a tube leading from said 55 condenser tank, substantially as described.

2. In a hydrogen gas generator, the combination of a compartment, a feed reservoir above the compartment and in communication therewith, a condenser tank, a plurality

of partitions in the condenser tank, the opposite portions of the adjacent partitions being perforated for establishing communication from one side thereof to the other, a conduit extending from said compartment to the space between an end of said condenser tank and the first partition, and a tube leading from the space between the one end of the condenser tank and the last partition, substantially as described. 65 70

3. In a hydrogen gas generator, the combination of a compartment, a feed reservoir above the compartment and in communication therewith, a horizontal condenser tank above said compartment, a plurality of 75 transverse partitions in the condenser tank separating it into sections, the upper and lower portions of adjacent partitions being perforated for establishing communication from one side thereof to the other, a conduit 80 extending from said compartment to one of said end sections to the condenser tank and a tube leading from the other end section of the condenser tank, substantially as described.

4. In a hydrogen gas generator, the combination of a compartment, a feed reservoir above the compartment and in communication therewith, a horizontal condenser tank above said compartment, a plurality of 90 transverse partitions in the condenser tank separating it into sections, the upper and lower portions of adjacent partitions being perforated for establishing communication from one side thereof to the other, a conduit 95 extending from said compartment to one of said end sections to the condenser tank, a tube leading from the other end section of the condenser tank, and the lower edges of said compartments being provided with drainage openings, substantially as described. 100

5. In a hydrogen gas generator, the combination of a compartment, a box in the compartment, the box having a top adapted 105 to support spelter, the top being perforated, a feed reservoir above the compartment for containing a solution of water and oil of vitriol, the reservoir being provided with an opening at its top, a pipe extending from the reservoir into said box, a condenser tank, a conduit extending from the top of said compartment to the bottom of said condenser tank, a tube extending from the top of said condenser tank, the tube terminating in a 110 nozzle member, and a shut-off valve for the nozzle member, substantially as described. 115

In testimony whereof I affix my signature.

ARTURO G. FAUZON.
